(57) **CLAIM**

The ornamental design for a spinning spool winder, as shown and described.

DESCRIPTION

FIG. 1 is a perspective view of one embodiment of a spinning spool winder according to the present invention.

FIG. 2 is a front elevated view of the spinning spool winder of FIG. 1.

FIG. 3 is an elevated back view of the spinning spool winder of FIG. 1.

FIG. 4 is an elevated side view of the spinning spool winder of FIG. 1; and,

FIG. 5 is a perspective view of the spinning spool winder of FIG. 1 shown in its environmental use.

The broken line showing of a spool in FIG. 5 is for illustrative purpose only and forms no part of the claimed design.
